TOBACCO STICK

William A. Mish, Jr., P.O. Box 264, Washington, N.C.
Filed Aug. 14, 1963, Ser. No. 302,028
6 Claims. (Cl. 294—5.5)

My present invention relates to tobacco sticks or laths, such as are used to hold green tobacco leaves during the curing thereof in a tobacco curing barn or the like. More particularly my invention is an improvement of my prior co-pending patent application Serial Number 237,705, filed November 14, 1962, now Patent No. 3,107,018, entitled Double Handle Tobacco Stick, and is a continuation-in-part of my prior application Serial Number 155,055, filed November 16, 1961, now abandoned, entitled Double Handle Tobacco Stick.

The subject matter of the above identified applications has been very satisfactory in use and the subject matter thereof has been commercially successful. The devices of these applications have their respective component parts when once assembled permanently held together as a unit and are so assembled by the manufacturer.

It is an object of this invention to provide an improved tobacco stick wherein the component parts thereof are distributed in a knocked-down condition and may be assembled for spot use after delivery from the manufacturer without the use of bolts, nuts, screws or the like.

Another object is to provide an improved novel articulating means for tobacco stick assemblies of the type described, which include spaced bar means pivoted together in spaced relation, whereby the bar means of the stick assembly may be articulated to and from tobacco leaf loading and unloading positions with optimum facility.

A specific object of my invention is to provide a novel hinge and bar spacer for the holder bars of such tobacco sticks.

Another object is to provide a spring fastener adapted to yieldably clamp into operative position on one of the holder bars of the stick.

Still another object is to combine the desirable features of my prior co-pending applications into a novel tobacco stick assembly, with individual prefabricated spaced holder bars whereby said prefabricated individual holder bars may be quickly and simply selected from a kit and assembled for loading green tobacco leaves and for unloading cured or dried tobacco leaves.

Another object is to provide a novel knockdown double tobacco stick arrangement including independent separate prefabricated bars adapted to be assembled together in operative position by a novel separable hinge means adapted to slide and clip onto one end of one of the stick bars and a separable fastener adapted to clip onto the opposite end of one of the bars of the stick.

Still further objects and advantages of my present novel improvements will be apparent from the following description when read in conjunction with the accompanying drawings, wherein like numerals and letters throughout the following figures identify similar parts of the invention.

In the drawings:

FIGURE 1 represents an assembled tobacco stick of the double handle two bar type loaded with green tobacco leaves prepared for hanging in a curing barn or like curing enclosure;

FIGURE 2 represents an assembled tobacco stick of the double handle two bar type unloaded and showing one bar means in solid lines raised to a loading position above the second bar and with the said bar shown in dotted lines in a lowered position after the tobacco stick is loaded in tobacco leaf holding position;

FIGURE 3 is a cross section view taken on section line 3—3 of FIGURE 1 at the connection point of my novel combined bar spacer and hinge;

2

FIGURE 4 is a perspective view of the novel clip on combined bar spacer and hinge of my invention;

FIGURE 5 is a cross section view at the connection point of the novel clip on latch of my invention taken along section line 5—5 of FIGURE 1.

Referring to the drawings and first with particular reference to FIGURE 2, my novel tobacco stick T is comprised of prefabricated components, namely, a first bar A with an elongated groove 11 extending longitudinally from end to end thereof and offset from the longitudinal center line of the bar; a second bar B with a longitudinal row of elongated spikes 12 having an aligned cluster of spikes 13 and 14 at each end of the spike row, which row of spikes is likewise offset from the longitudinal center line of the bar B; a combined bar spacer and hinge C adjacent the spaced ends of the bars A and B at one end of the stick T and a snap on latch means D adjacent the opposite spaced ends of the bars A and B, see FIGURES 1 and 2.

Each of the component parts A, B, C and D of the tobacco stick T are prefabricated by the manufacturer or producer and may be distributed in a knockdown condition in a package or kit, not shown, for distribution and sale to customers with directions for assembly. For example, the tobacco stick spike bar B is prefabricated and includes the longitudinally spaced row of spikes 12. Also, the spike bar B in its side walls 15 and 16, see FIGURE 3, adjacent each end is formed with aligned sockets 17 and 18 for mounting the combined bar spacer and hinge C and with aligned sockets 19 and 20 in the side walls 15 and 16 adjacent the opposite end, see FIGURE 5, for mounting the latch means D.

The bars A and B when assembled together to the combined bar spacer and hinge C may be positioned as to leave an extension 23 from bar B at respective opposite ends of the stick T, see FIGURES 1 and 2. These extensions provide handles to facilitate handling and supporting the assembled stick on suitable racks in curing enclosures.

The Hinge (FIGURE 4)

My novel bar spacer and hinge structure is in effect a thread on arrangement for resilient frictional engagement with the prefabricated structure of the bar A of the tobacco stick T. For example, the combined bar spacer and hinge C is made from a single strand of spring steel wire or a predetermined length of spring steel bar stock looped and formed into a double L-shaped formation with two parallel leg portions 25 and 26 and two inwardly curved or arcuate base portions 27 and 28 extending from the respective leg portions in a plane substantially at right angles thereto. The respective diverging ends of each arcuate portion 27 and 28 are bent at substantially right angles in the provision of bar side gripper means 29 and 30, respectively, and the integral loop 31 of the double-L base portions 27 and 28 is then reversed to extend above the plane of the double-L base portions toward the legs 25 and 26 and the loop 31 is formed with a rounded nose portion 32, which extends between and terminates rearwardly of the spaced legs 27 and 28 of the combined bar spacer and hinge C, see FIGURE 4. Finally, the free ends of each of the spaced legs 27 and 28 are bent inwardly toward each other at substantially right angles in the provision of aligned but spaced apart hinge pins 33 and 34, respectively.

As stated above, the stick bars A and B are factory prefabricated and the elongated bar A is preferably made to be rectangular in cross section with side surfaces 35 and 36 and bottom surfaces 37 and 38, see FIGURE 3. Each surface of the bar A is frictionally engaged by a yieldable spring part of the double-L formation of the combined bar spacer and hinge C, when it is

mounted on an end of the bar A. Thus the combined bar spacer and hinge C is threaded and frictionally engaged over an end of the bar A, see FIGURE 2, so the yieldable spring parts 29 and 30 each frictionally engage one of the sides 35 and 36 of the bar, and the arcuate parts 27 and 28 engage under the bar over its bottom surface 37 and the loop 31 engages over the top grooved surface 38 of the bar A.

When thus positioned on the bar A, the spaced legs 25 and 26 extend vertically from the bar surface 38 and are in position to be spread apart from their normal parallel relation for insertion of the hinge pins 33 and 34 into the sockets 17 and 18 in an end of the second bar B, see FIGURES 1, 2 and 3. Since the entire hinge C is made from a single piece of spring steel bar stock, when the legs 25 and 26 are manually spread apart, normally aligned hinge pins 33 and 34 will snap into the sockets 17 and 18 by spring action in the bar B when released for return to their normal positions, whereby the end of bar B becomes hinged to the bar A and spaced with respect thereto for a distance substantially equal to the length of the elongated tobacco leaf spikes 12 and the respective spike clusters 13 and 14 at each end of the bar B. FIGURE 2 shows how the respective tobacco stick bars A and B are hinged and spaced by the means C and how they may be articulated to and from a loading and a latched together loaded leaf position.

The Bar Clip On Latch Means

The opposite spaced ends of the bars A and B are provided with a novel boltless and nutless friction mounted latch means D. This means comprises a continuous rectangular loop formed of spring steel wire or bar stock slotted at one end to provide opposed aligned pins 38 and 39. These pins are adapted to snap fit into the sockets 19 and 20 of the bar A and each pin supports a U-shaped plate 40 and 41, respectively.

Each of the plates 40 and 41 frictionally fit on each side of the bar B, see FIGURES 2 and 5, and on their respective exterior faces are formed with latch keeper means comprised of spaced projections 42 and 43. These projections serve to hold the latch means in bar latching position as is clearly illustrated in FIGURE 2 of the drawing.

In FIGURE 1 of the drawing, the tobacco stick is shown latched and loaded with tobacco leaves F. These leaves are held by their respective leafy portions below the stem area by the offset row spikes 12 in bar B which line up with the longitudinal offset groove 11 in bar A.

The expanse of the oppositely facing sides of the bars A and B above the spike row 12 and the mating groove 11 serves as a support for the tobacco leaves at the stem area above the leafy spiked area of the leaves. This area is provided to support the tobacco stem area of the leaves during curing as the stems become limp in the curing barn and need support to prevent stem curling.

Thus there is provided a novel tobacco stick assembly of the spaced bar type, including a combination bar spacer and hinge and a novel clip on latch means for holding the bars together in a tobacco leaf holding position.

Also, there is provided a novel tobacco stick of the spaced bar type which is of the knockdown delivery type and which is readily assembled without bolts, nuts or screws by means of a novel bar spacer and hinge of spring material and by means of a latch means likewise of spring material.

Without further description it is believed that the advantages of the present invention over prior tobacco sticks of this type is apparent and while only one embodiment of the same is illustrated, it is to be expressly understood that my invention is not limited to such one embodiment as various changes may be made in the arrangement and combination of parts, as will now likely appear to others and those skilled in the art. For a

definition of the scope or limits of my invention, reference should be had to the appended claims.

What I claim is:

1. A boltless knocked down tobacco stick including a plurality of prefabricated parts comprising a bar having a longitudinal row of elongated spikes, said bar having aligned sockets, one in each side thereof, adjacent to one end, another bar having a longitudinal groove in a surface thereof co-terminus the length of said bar, said groove serving to receive the free ends of said spikes in the first mentioned bar, a bar spacer and hinge frictionally mounted on said second mentioned bar, said hinge comprising a continuous loop of spring metal rod, said loop being a double-L formation with spaced vertical and horizontal legs, said vertical legs having aligned pivot projections at the ends and a reversed loop portion connected to and extending in a plane above said horizontal legs between said vertical legs, portions of the horizontal legs, the vertical legs and the reversed loop frictionally engaging the surfaces defining the top, bottom and sides of said second mentioned bar, and said aligned pivot projections being engaged in aligned sockets of said first mentioned bar, and a latch means frictionally mounted on said first mentioned bar, said latch means being movable to a latching position to hold the spike ends in the groove of the second mentioned bar when the said plurality of prefabricated parts are assembled from a knocked down condition.

2. A knockdown tobacco stick comprising spaced first and second bars and including boltless bar connecting means formed of spring material, said means comprising a continuous loop of spring material, said loop being a double-L formation with spaced vertical and horizontal legs, said vertical legs having aligned pivot pins and said horizontal legs forming a base, a reversed loop portion extending in a plane above said horizontal legs between said vertical legs, said base frictionally engaging the surface of a first bar and said pivot pins engaging the sides adjacent an end of a second bar spaced apart from said first bar, and latch means formed of spring material yieldably engaged with the opposite end of said first bar for holding the bars together in a substantially spaced parallel relation.

3. A boltless knockdown tobacco stick as described in claim 2, wherein the said latch means comprises a rectangular loop of spring steel bar stock, said loop being slotted at one end to provide opposed pins and bar clamp means carried by said pins, said clamp means being shaped to embrace the sides of said second bar, and latch keeper means on an exterior surface of each of said bar clamp means.

4. A combined bar spacer and hinge for a boltless knockdown tobacco stick of the spaced bar type comprising a strand of steel spring wire formed with spaced upstanding legs, said legs having inwardly facing pivot pins, and a base portion comprising spaced arcuate formations, a continuous loop reversely extending in a plane above said arcuate formation toward said legs and bar side engaging sections parallel to the legs connecting each of the arcuate formations with spaced portions of the said loop.

5. In a tobacco stick assembly for impaling green tobacco leaves to be cured comprising

(I) a pair of spaced rigid bars, one of said bars being spaced from the other bar with the ends of one bar opposite to the ends of the other bar;

(II) bar end embracing members of spring material at each of the ends of said spaced bars;

(III) said bars at their respective ends being spaced apart by each of said first and second opposed bar end embracing members in substantially parallel relation;

(IV) the first of said bar end embracing members being pivoted to one of the bar ends and releasable from an opposed bar end of the other one of said bars;

(V) the second said bar end embracing member com-

- prising a combined bar spacer and hinge with spaced pivot pins in connection with an end of one of said bars to provide a pivot axis permitting said bars to swing apart at the opposite end throughout their respective lengths when said first pivoted releasable bar end embracing member of spring material is released from its engaged end of one of said rigid bars; 5
- (VI) one of said rigid bars having a plurality of longitudinally spaced elongated rods with pointed ends; 10
- (VII) said elongated rods being embedded at their ends and offset in said one bar transverse their respective widths with respect to a longitudinal axially extending line for substantially the length of said one bar; 15
- (VIII) the opposed surfaces of the bars having the greater expanse of the respective bar widths extending from the said longitudinal axial line above the axially aligned offset rods providing a tobacco leaf stem support section; 20
- (IX) said support section provided by the opposed surfaces having the greater expanse of said bar widths above the said offset longitudinal axial line of the rods providing an area allowing for the spread apart support of the extended stems of the green tobacco leaves impaled by said rods; 25
- (X) green tobacco leaves being impaled by only the elongated rods extending through the leaf portions below said spread apart stems in the support section; and 30
- (XI) said rods being spaced apart a predetermined distance along said offset axial longitudinal line and with respect to the width of each of said bars to permit air circulation through the said tobacco leaves impaled on said rods of the stick. 35
6. In a tobacco stick assembly of prefabricated parts for impaling green tobacco leaves to be cured comprising 35
- (I) a pair of bars one of said bars being spaced from the other bar with the ends of one bar opposite to the ends of the other bar; 40
- (II) bar end embracing members of steel spring bar stock at each of the ends of said bars yieldably mounted on one of said bars; 45
- (III) said bars at their respective spaced ends when assembled being spaced apart by each of said opposed bar embracing members in a substantially parallel tobacco leaf impaling position; 50
- (IV) one of said opposed bar end embracing members serving as a latch and being releasable from one of said bars; 55
- (V) one of said embracing members including a transverse pivot pin connection at an end of one of said bars to provide a pivot axis permitting said bars to

- swing apart at the opposite end throughout their respective lengths when said releasable bar end embracing latch member is released from the end of one of said bars; 60
- (VI) one of said bars having a plurality of longitudinally spaced long rods with non-pointed and pointed ends; 65
- (VII) said rods being embedded at their non-pointed ends along a longitudinal axially extending line for substantially the length of said one bar in which said non-pointed ends are embedded; 70
- (VIII) said respective opposed surfaces of the bars when in said substantially parallel relation are used for impaling tobacco leaves having the greater expanse of the respective bar widths extending from the said longitudinal axial line on one side of the axially aligned leaf impaling offset rods; 75
- (IX) said opposed surfaces when positioned vertically for use having the greater expanse of said bar widths at one side of the said offset longitudinal axial line of the rods providing an area allowing for the spread apart support of the extended stems of the tobacco leaves impaled by said rods; 80
- (X) tobacco leaves being impaled at the leaf portions below said spread apart stems; 85
- (XI) said rods being spaced along said offset axial longitudinal line and with respect to the width of each of said bars to permit free air circulation through the said tobacco leaves impaled on said rods of the stick; 90
- (XII) an elongated longitudinal groove in said other bar, said groove being in alignment with said pointed end of each of said rods in the first mentioned bar when the bars are pivoted together, said groove serving as a leaf loading gauge line for accurate positioning of leaves on the bar with the groove when the bars are swung apart on said pivot pin connection, and said groove enclosing the ends of the rods, thereby preventing the leaves from slipping around the pointed ends of the rods when the bars are latched together by said bar end embracing latch member in said substantially parallel leaf impaling relation. 95
